SIDNEY Y. BALL, OF CLEVELAND, OHIO, ASSIGNOR TO THE WEBB C. BALL WATCH COMPANY, OF CLEVELAND, OHIO, A CORPORATION OF OHIO.

DESIGN FOR A BADGE.

No. 38,542.

Specification for Design.

Patented April 30, 1907.

Application filed March 20, 1907. Serial No. 363,525. Term of patent 3½ years.

To all whom it may concern:

Be it known that I, SIDNEY Y. BALL, a citizen of the United States, a resident of the city of Cleveland, in the county of Cuyahoga, State of Ohio, have invented a new, original, and ornamental Design for Badges, of which the following is a specification, reference being had to the accompanying drawing, forming a part thereof.

The single figure appearing on such drawing is a plan view of a badge showing my new design.

I claim:

The ornamental design for a badge as shown.
